UNITED STATES PATENT OFFICE.

CHAUNCEY C. BUCK, OF EVANSTON, ILLINOIS.

STORAGE RACK.

Application filed July 19, 1923. Serial No. 652,554.

To all whom it may concern:

Be it known that I, CHAUNCEY C. BUCK, citizen of the United States, residing at Evanston, in the county of Cook and State of Illinois, have invented certain new and useful Improvements in Storage Racks, of which the following is a specification.

This invention relates to improvements in storage racks and more particularly to racks for storing pianos and the like.

Prior to the present time it has been a general practice to store grand pianos on edge as nearly all warehouses do this in order to utilize the space to the best advantage. As grand pianos have become quite popular in late years, storage warehouses usually have as many grand pianos for storage as they do uprights, and as storing the grand pianos on their sides is very injurious to the highly polished surfaces as well as detrimental to the interior of each piano if left in that position long, it is the primary purpose of this invention to furnish means for storing grand piano bodies one above the other, with each piano resting on its own bottom.

Another object of the invention is to furnish a storage rack having a number of horizontal shelves or brackets adapted to be moved outwardly beyond the frame of the rack in order to receive a piano body and then to be moved into the frame for the purpose of supporting the piano body in a horizontal position.

Another object of the invention is to furnish detachable adjustable supports or struts which may be moved from one shelf to the other for the purpose of supporting the shelf bracket when the bracket is moved outwardly to receive or discharge its load.

A further object of the invention is to furnish a detachable buffer bar adapted to be attached to the movable brackets of each shelf and to abut against the edge of the piano body, and prevent marring of the polished surface of the latter.

The rack is constructed principally of angle iron and strap iron and is made up in sections so that sections may be added as required, or be detached when not required.

With the foregoing objects outlined and with other objects in view which will appear as the description proceeds, the invention consists in the novel features herein-after described in detail, illustrated in the

accompanying drawings and more particularly pointed out in the appended claims.

Referring to the drawings:

Figure 1 is a vertical sectional view of one section of the rack.

Fig. 2 is a perspective view of the detachable buffer bar employed with the movable brackets.

Fig. 3 is a front view partly in section of one of the carriages forming part of each movable bracket.

Fig. 4 is a horizontal sectional view of the rack taken on the line 4—4 of Fig. 1.

Fig. 5 is a detail perspective view showing the manner of connecting one end of a shelf track to one of the horizontal bars of the frame.

Fig. 6 is a vertical sectional view of a detail illustrating the manner of connecting the buffer bar to one of the movable brackets.

Fig. 7 is an enlarged view partly in section of the upper shelf of the rack section shown in the drawing.

Fig. 8 is a perspective view partly in section of one end of a rack section, and illustrating the manner of connecting the same to an additional section.

Fig. 9 is a perspective view of one of the supports or struts used for supporting the bracket when the bracket is in its projected position.

The section of the rack illustrated in the drawings preferably consist of four vertical angle iron posts, the front two of which are connected together by horizontally disposed angle iron cross bars 2, and the rear two posts of which are connected by angle iron horizontal cross bars 3. Each pair of end posts are connected together by horizontal straps 4 and 5 and crossed bracing straps 6 and 7. These straps are bolted together as shown at 8 and are bolted to the posts as shown at 9. The construction so far described forms the frame of one section of the rack and the horizontal cross bars 2 and 3 of this frame are provided with abutment members or wooden blocks 10 and 11. Shelf tracks 12, preferably of angle iron construction, rest on these blocks and are secured in position by bolts 13. Each one of these shelf tracks 12 is provided with a slideable bracket 14 of angle iron construction, the horizontal portion of which slides on the horizontal portion of the track 12 with which it is associated.

As best shown in Figs. 1 and 3, each angle iron bracket 14 is

secured at 15 to an inverted U-shaped yoke 16 having the lower end of its legs connected together by a cross pin 17, which extends beneath the track 12 with which the bracket 5 is associated. A bolt 18 also extends across the yoke 16 and carries a roller 19, which as shown in Figs. 1 and 7, rolls on the horizontal portion of the track. As shown in Figs. 1, 3 and 7, the pin 17 extends beneath 10 the track 12 for the purpose of engaging the lower edge of the track 12 when the bracket 14 is projected forwardly as shown in dotted lines in Fig. 1. When the bracket is in this position, it is adapted to receive a piano 15 body.

Each bracket 14 is provided at its forward end with an angle iron lug 20. It will be noted that there are two tracks 12 and two brackets 14 for each shelf and in use the two 20 brackets 14 of a shelf are to be moved forwardly at the same time, and at this time the buffer bar 21, best shown in Fig. 2, may be attached to the two brackets. For this purpose the base 22 of the buffer is provided 25 near its ends with sockets 23 adapted to engage the upwardly extending portions of the lugs 20, as shown in Fig. 6. From this figure it will be observed that the base 22 of the buffer bar supports padding 24, and a 30 cover 25 secures this padding to the base. When two of the brackets 14 are in their forwardly projecting position as shown by dotted lines in Fig. 1, and the buffer bar 21 is attached to the lugs 20 of these brackets, 35 the piano body may be lifted onto the brackets and its edge will abut against the buffer bar 21, and the latter will prevent marring of the polished surface of said edge. It is to be noted that the buffer bar is movable or 40 transferable from shelf to shelf, that is, after it has been used with the brackets on the lower shelf it may be transferred to the brackets of the next shelf above and so on.

The apparatus also includes adjustable 45 supports or struts 26 to bear the weight of the brackets 14 when said brackets are in projected position. Each of these struts has an inverted U-shaped yoke or socket 27 at its lower end adapted to detachably engage 50 either of the cross bars 2, and each strut is provided in its upper end with a cross head 28 to engage the lower edge of the bracket 14. As shown in Fig. 4, there are two of 55 these struts, one for each bracket 14 of a shelf.

The blocks 10 and 11 function as abutment members for the bolt 17 when a bracket 14 is moved either forwardly or rearward.

In use, when it is desired to store piano 60 bodies, the lower brackets 14 may be slid forwardly and the buffer bar 21 attached to the lugs 20 of these brackets. Then the piano body may be placed on the two brackets and then the brackets may be slid into the frame until the yokes 16 abut against the

lower blocks 11. Then the buffer bar 21 may be removed and attached to the lugs 20 of the brackets 14 immediately above, and if desired the struts 26 may be attached to the lowermost cross bar 2. Then the second 70 brackets 14 with the buffer bar attached to the same may be slid forwardly and rest on the heads 28 of the struts 26 to receive a second piano and so on.

As shown in Fig. 8, the construction is 75 such that additional sections may be added simply by attaching additional cross bars 3^a and 2^a to the posts 1 at one end of the first mentioned section. It will of course be necessary to connect the opposite ends of the 80 bars 2^a and 3^a to posts, but these posts are not shown in the drawings. In order to make the device of portable or knock-down construction, the various fastening means are preferably bolts and nuts.

From the foregoing it is believed that the construction, operation and advantages may be readily understood by those skilled in the art and it is apparent that various changes may be made without departing from the 90 spirit of the invention as expressed in the claims.

What is claimed and desired to be secured by Letters Patent is:

1. A rack including a plurality of substantially horizontally disposed stationary rails, a bracket bar slidably mounted on each of said rails, and means connecting each of said rails and its associated bracket bar to permit the bar to automatically swing 95 downwardly relatively to one end of the rail without detaching the bar from the rail, when the bar is moved forwardly relatively to the rail.

2. A rack as claimed in claim 1 in which the last mentioned means includes a yoke fixedly connected to one end of said bracket bar and provided with a cross pin adapted to slidably engage the underside of said rail.

3. A rack as claimed in claim 1 in which the last mentioned means includes a yoke fixedly connected to one end only of said bracket bar, a cross pin connected to the yoke and slidably engaging the underside of said rail, and a roller mounted on said yoke 110 and engaging the upper side of said rail.

4. The combination with a rack having superposed pairs of horizontally arranged rails, of a pair of combined sliding and swinging shelf brackets connected to each 115 pair of rails, and an interchangeable buffer bar adapted to be detachably connected to either pair of brackets.

5. A rack as claimed in claim 1 including a buffer bar detachably connected to the outer ends of said bracket bars.

6. The combination with a rack having superposed pairs of horizontally arranged tracks, of a pair of combined slidable and swinging shelf brackets connected to each 130

pair of tracks, superposed front rails connected to the front ends of each pair of tracks, and struts constructed to be interchangeably and detachably connected to either of said rails for supporting either pair of the brackets when the latter are in their outer positions.

7. A rack as claimed in claim 1 including vertically adjustable struts adapted to support said bracket bars, said rack also including corner posts, horizontal end bars and horizontal cross bars connecting said posts.

8. The combination with a rack having combined slidable and swinging shelf brackets, of vertically adjustable struts adapted to support said brackets, said rack including corner posts, horizontal end bars and horizontal cross bars connecting said posts, rails supported by said cross bars, each bracket being mounted on one of said rails, a yoke connected to said bracket and having a cross pin extending beneath the rail with which the bracket is associated, and a roller mounted in said yoke and engaging one of said rails, said vertically adjustable struts being adapted to be transferred from one cross bar to another and to support said brackets in certain positions.

9. A storage rack including corner posts,

end bars connecting said posts, superposed horizontal front and rear cross bars connecting the posts, superposed pairs of horizontal tracks carried by the cross bars, a bracket for each track including a rail, a yoke connected to the rear end of each rail and carrying a roller which rests on the upper surface of the track with which the rail is associated, a cross pin carried by the lower end of the yoke and adapted to engage the under side of the track when the rail is in its forwardmost position, the front end of the rail being adapted to slide outwardly and to gradually move downwardly when the rail is pulled forwardly.

10. A storage rack as claimed by claim 10 in which each bracket is provided at its outer end with a lug, and a buffer bar having sockets adapted to receive the lugs of either pair of said superposed brackets.

11. A storage rack as claimed in claim 10 including struts provided at the lower ends with fingers adapted to detachably engage either of said cross bars for supporting the brackets when the latter are in their outermost positions.

In testimony whereof I affix my signature.

CHAUNCEY C. BUCK.
